DISAPPEARING STAIRWAY

Frank E. Bessler, Akron, Ohio, assignor to The Bessler Disappearing Stairway Company, Akron, Ohio, a corporation of Ohio

Application October 26, 1932. Serial No. 639,678

3 Claims. (Cl. 228—50)

This invention relates to disappearing stairways of the ceiling panel type.

Heretofore stairways of this type have employed control mechanism including one or more spring drums, sheaves, etc., which are furnished by the manufacturer to be located by the purchaser on or adjacent to the frame of the ceiling opening through which the stairway operates. This requires some degree of skill on the part of the purchaser in installing the stairway so that the several parts of the control mechanism will function properly. In many cases installations are poorly made, resulting in early and frequent breakage of cables, spring drums, etc.

15 The general purpose of the invention is to provide a stairway construction in which all of the parts of the control mechanism are carried upon some part of the stairway construction as furnished by the manufacturer with the exception 20 of two small brackets attached on or adjacent to the frame of the opening for securing the ends of the flexible tapes or the like by which the stairway is controlled, brackets which do not require more than ordinary skill in placement, the 25 balance of the parts including all spring drums etc. being located by the manufacturer on the stairway parts furnished by him.

30 A further purpose of the invention is to provide a simplified and less expensive disappearing stairway construction with a minimum of parts and these of simpler, more economical construction.

35 The foregoing and other purposes of the invention are illustrated in the accompanying drawings and described below. It is to be understood that the invention is not limited to the particular form thereof shown and described.

Of the accompanying drawings,

40 Figure 1 is a side elevation, partly in section, showing a stairway installation embodying the invention in an extended position for use;

Figure 2 is a front elevation, partly in section, on line 2—2 of Figure 1;

45 Figure 3 is a side elevation, partly in section, showing the stairway retracted when not in use; and

Figure 4 is a section in part along line 4—4 of Figure 1.

50 Referring to the drawings the numeral 10 designates a frame defining a ceiling opening upon one end of which is hinged, as at 11, a panel 12. Above the hinged end of the panel there is provided a bracket or brackets 13 secured to the end of frame 10 and having pivoted thereon supporting and guiding bracket 14 of a known con-

struction having lugs as at 15 for engaging in grooves 16 on the outer sides of the stair structure 17 to slidably support the stair structure on said pivoted bracket.

60 Adjacent the free end of the upper side of the panel at each side thereof there are affixed brackets 18, 18 having swiveled lugs 19, 19 of a known construction for engaging in grooves 16 slidably to support the stair structure on the free end of the panel 12.

65 The weight of the extended stair structure 17 is off-set by provision of a spring-rewinding drum 20 of a known construction on the under side of bracket 14 from which is extended one end of a flexible tape 21 wound about said drum and having its other end secured thereto, the extended end of said tape being secured to the stair structure as at 22.

70 To off-set the weight of the panel and stairway structure when the latter is retracted thereon and to hold the panel shut, spring-rewinding drums 23 are mounted at each side of the free end of the panel preferably on brackets 18 and flexible tapes 24, 24 wound on said drums and having their inner ends secured thereto are extended from said drums to brackets 25, 25 adapted to be secured to each side of the frame 10. The weight of the stair structure and panel when the latter is extended as shown in Figure 1 is sufficient to overcome the rewinding force of the 85 spring drums 23. When the weight of the upper portion of the stair structure is effective on the opposite sides of the pivots of brackets 14 upon retraction of the stairway, the spring drums 23 then become effective to swing the panel 12 shut 90 carrying the stair structure up through the ceiling opening to its retracted position shown in Figure 3.

95 The stair structure is preferably latched in its retracted position on the panel by latches 26 engaging keepers 27 as the stairway is retracted. The particular latching arrangement shown is illustrated in detail in the United States patent to Bessler, No. 1,636,281, granted July 19, 1927.

100 To operate the stairway from the position shown in Figure 3 to the position shown in Figures 1 and 2, the panel 12 is first swung downwardly. This is accomplished from the lower floor by pulling down the panel from below, a 105 chain 12^a depending from the panel preferably being provided for this purpose. The panel may be opened from the upper floor by lifting the upper end of the stair structure. The stairway is then extended by pulling it down from the 110

lower floor or pushing it down from the upper floor.

It will be noted that the improved structure utilizes only three comparatively inexpensive 5 spring-rewinding drums and no sheaves or other guides. The spring drums are all located on stairway parts by the manufacturer and the purchaser has only to locate the brackets 25 of the control mechanism.

10 Modifications of the invention may be resorted to without departing from the spirit thereof or to the scope of the appended claims.

What is claimed is:—

1. A disappearing stairway comprising a panel 15 adapted to be hinged to one end of a frame defining a ceiling opening, a stairway supporting bracket adapted to be pivotally mounted on said end of the frame above the panel hinge, brackets secured at each side of the panel adjacent the 20 free end thereof, a stair structure slidable on said pivoted bracket and on said brackets on the panel, a spring-rewinding drum secured to said pivoted bracket and having a tape wound thereon and connected with said stair structure, 25 spring-rewinding drums one secured at each side of the panel on said brackets adjacent the free end thereof, and brackets one adapted to be secured at each side of said frame, said last-named spring-rewinding drums having tapes wound 30 thereon and extended to said brackets.

2. The combination in a disappearing stairway

installation of a frame defining a ceiling opening, a panel hinged at one end to the frame, a support pivoted to said end of the frame above the panel, a stair structure slidable on said support, means adjacent the free end of the panel 80 slidably supporting the stair structure thereon, a spring-rewinding drum on said pivoted support having a flexible element wound thereon and extended and secured to said stair structure, and spring-rewinding drums one at each side of the free ends of the panel on said supporting means and having flexible elements wound thereon and extended and secured to said frame.

3. The combination in a disappearing stairway 85 installation of a frame defining a ceiling opening, a panel hinged to one end of said frame, a stair structure, a support for the upper portion 90 of the stair structure on which the stair structure is slidable, said support having a pivotal movement with movement of the panel, means for supporting the stairway on the panel adjacent its free end, said stair structure being slidable on said support and said supporting means, a spring-rewinding drum on said support having 95 a flexible element wound thereon and extended and secured to the stair structure, and spring re-winding drums, one on each side of the panel on said supporting means each having a flexible element wound thereon and extended and secured to said frame.
